WEAVING LOOM FOR CONTINUOUS WEAVING IN WHICH THE WEFT IS INSERTED BY MEANS OF PIRNLESS SHUTTLES

Raymond Dewas, Amiens, France

Application June 17, 1933, Serial No. 676,251
In France June 23, 1932

10 Claims. (Cl. 139—125)

The present invention relates to improvements to the invention described in my pending U. S. application filed May 31, 1933, Ser. No. 673,672, for "improvements in Weaving looms for continuous weaving in which the weft is inserted by means of pirnless shuttles".

The improvements which are the object of the present invention have for their aim the possibility of allowing the weft to pass alternately from either side of the loom by means of weft threads fed from two large bobbins of which one is arranged on each side of the selvedges.

As in my above-mentioned application, these improvements enable looms which are provided with them to work at a very high speed and in any position, horizontal, oblique or vertical, in that the insertion member with equal facility can be thrown across the shed horizontally, obliquely or vertically.

20 The improvements also enable the shuttle to be thrown alternately from each side of the loom, either by throwing devices arranged at each side of the selvedges and provided with discs of the type described in the above mentioned application, or by means of picking sticks or rods of the already known type, or finally, by means of electro-magnets in which the direction of the current would be alternately reversed, etc.

Further, the improvements make it possible, by using the members described in the above-mentioned application but disposing them symmetrically on each side of the selvedges, to present the weft and to release it, as well as to cut the weft with or without turning-in the end of the preceding shoot whereby the selvedges may or may not be formed, as the case may be.

Finally, these improvements can be employed on looms having shuttle boxes which form part of the sley, or which are rigidly fixed, so that the reed and the sley, which may or may not include a shuttle race are the only movable parts.

In accordance with the invention described in the above entitled patent application, the process of insertion of the weft in the shed, in a single weft thread coming from a stationary bobbin, with a fast selvedge is characterized by the feature that the weft thread is stretched in front of and across the opening of the shed, between the selvedge and the weft bobbin, and is seized by the weft inserter after this inserter has been driven and at the time of its entry into the shed, and is cut by a cutting device which is integral with the inserter, in such a manner that the portion of weft thread which lies between the inserter and the selvedge is folded into the

shed by the inserter entering the said shed, so as to form the fast selvedge, and that the portion of weft thread which lies between the inserter and the bobbin, from which the weft thread can run off or unwind, is passed into the same shed as a single thread and is released from the inserter when it comes out of the shed.

This process, when a fast selvedge on one side of the fabric is not required, is characterized by the feature that the weft thread, stretched in front of the opening of the shed, between the selvedge and the bobbin, is seized by the inserter, at its entry into the shed, and is cut by a cutting device, which is in this case not integral with the inserter but is arranged externally and in front of the opening of the shed between the point of the fell of the cloth and the path of the inserter, in such a manner that the portion of weft thread which lies between the inserter and the point of the fell of the cloth with the selvedge remains free outside of this point. Furthermore, the portion of weft thread which lies between the inserter and the bobbin, from which the weft thread can run off or unwind itself, is placed inside the same shed as a single thread and released from the inserter when it comes out of the shed.

In certain cases, in order to insert in one of the selvedges one end of thread only out of two, there may be employed an inserter with a cutting device and a weft inserter without a cutting device, alternately.

If a cutting blade is carried by the inserter, it severs the thread coming from the preceding pick and going up to the bobbin, so as to realize a fast selvedge, without utilizing any actuated device.

As a weft inserter is shot into the shed, the weft stretched on its path is caught into the two prongs of the rider and held between the springy prongs of the clamp. As the inserter is continuing its stroke along into the shed, the weft, stretched between the eyelet and the fell of the cloth, is being bent into the entrance of the shed.

Under the tension of the thread thus bent, as the inserter progresses, the said thread slides between the springy branches of the clamp till it comes into contact upon the edge of the cutting blade, where it is cut.

The thus severed thread, allows the inserter to continue its stroke. The part of said severed thread, which is still held in the clamp and goes up to the bobbin, is carried along the shed to constitute the next pick, and the part of same

said severed thread which goes up to the fell of the cloth, remains in-turned into the entrance of the shed, to form the fast selvedge.

It is understood that, the passing of the weft alternately from each side of the loom, renders unnecessary the use of the unidirectional closed circuit employed for the passing of the weft from one side only of the loom, since both the ends of the conduit which are adjacent to each selvedge may be used as shuttle boxes; the device provided with discs, which throw the shuttle across the shed and back in the conduit for completing the circuit, also can be used equally well for throwing the shoot alternately, it being understood that in this case the discs of the above mentioned device are operated in such a manner that they will rotate in the opposite direction.

These improvements, which are the object of the present invention, relate, among others, to the following elements:

1. The member for inserting the weft, or pinnless shuttle, which is so arranged that it can grip the weft alternately on each side of the loom, cut it and release it.

2. The members which present, release and sever the weft.

As regards the member for inserting the weft or pinnless shuttle, which, according to the present invention, is adapted to insert the weft alternately from each side of the loom, this is similar to the insertion member described in the above mentioned application and consists of a rectilinear piece, preferably of metal, having an essentially triangular or trapezoidal cross section and which is split vertically in its middle plane at each end, for a certain length, while the central part which remains solid is provided on the side which faces the reed with a central groove in which is arranged a resilient clamp which can grip the weft thread from both ends, as will be explained hereinafter.

As regards the members for presenting and releasing the weft, according to the present invention, they consist, as in the above mentioned application, of an eyelet through which passes the weft thread coming from the bobbin and of a blade for pushing apart the prongs of the clamps, an eyelet and a blade being arranged on each side of the selvedges.

The said members are mounted on movable supports adapted alternately to move the eyelet into position for passing the weft thread on to the shuttle at the moment when the said shuttle enters the shed to pass the end of the thread through it, and to move the blade into position for forcing apart the prongs of the resilient clamp of the shuttle when the said shuttle, thrown from the opposite selvedge, has traversed the shed and carried the end of the weft through it.

As concerns the cutting members, these are the same as mentioned in the above mentioned application and consist of cutting blades either arranged in the shuttle itself beneath the level of the clamp, there being one blade for each direction of the motion of the shuttle, in order to enable selvedges to be formed by bending back the ends of the preceding shoots; or fixed on the loom at each side of the selvedges, if the ends of the weft are to remain outside of the woven material and at a later stage to be sheared off.

In order to explain the present invention more fully, and by way of an example of the application of the improvements which are its object,

several arrangements are described hereinafter and shown diagrammatically in the accompanying drawings in which:

Figure 1 is a side elevation of the weft inserting member;

Figure 2 is a plan view of the same weft inserting member showing the surface which slides along the reed and also showing the gripping clamp which is carried by the member and which is adapted to grip the weft thread at both ends;

Figure 3 is a plan view of the same weft inserting member showing the surface which faces the fell of the cloth, and illustrating the two slots and the central groove with which the member is provided;

Figure 4 is an end view of the same weft inserting member;

Figure 5 is a fragmentary plan view of the warp, of the sley, of the end of the conduit which constitutes the shuttle box, and of the movable members which present and release the weft, the presenting member being in position for gripping the weft, the weft inserting member being shown at its entry into the shed, the throwing device with discs or the like not being shown in this figure;

Figure 6 is a corresponding side elevation viewed from the end of the warp;

Figure 7 is a plan view similar to Figure 5 and showing the insertion member continuing its course through the shed;

Figure 8 is a plan view similar to Figure 5, showing the insertion member at the end of its return journey after having been thrown from the other selvedge, the movable members for presenting and releasing the weft having been so displaced that the releasing blade is in juxtaposition with the central slot and the clamp, while the presenting member is out of the path of the said insertion member for transporting the weft;

Figure 9 is a corresponding side elevation viewed from the end of the warp;

Figures 10 and 11 are similar views to Figures 5 and 6, showing the arrangement of the cutting member fixed adjacent to a selvedge, when the cutting member is arranged independently of the insertion member;

Figure 12 shows in elevation an alternative design for the member for inserting the end of the weft, when this member is intended to cooperate with fixed presenting and releasing members for the weft;

Figure 13 is a plan view of the weft inserting member, showing the surface which slides along the reed; and

Figure 14 is a plan view of the weft inserting member shown in Fig. 13 and shows the surface which faces the fell of the cloth;

Figure 15 is an end view, looking at the left hand end of the inserting member of Figure 13;

Figure 16 is the same view from the right hand end;

Figure 17 shows diagrammatically a resilient clamp carried by the weft inserting member;

Figure 18 is a section along the line 18—18 of Fig. 17.

Figures 1 to 4, show the inserting member 1 for the weft, which consists of a rectilinear piece of metal, preferably having a triangular or trapezoidal cross section, (Fig. 4) and provided with vertical slots 2 and 3 (Figs. 2 and 3), while the middle part, which is solid is provided, upon the face which slides on the reed, with a central

groove 4 which connects the two central opposite slots 2 and 3.

In this groove or slot 4 the clamp for holding the weft thread is arranged, said clamp being shown separately in Figs. 17 and 18, and comprising two straight flexible steel prongs 5 arranged parallelly and in elastic contact, the one against the other, in the centre of the groove 4, so as not to come into contact with the walls 10 of the said groove, the ends 5a of these prongs being bent back towards the said walls in which they are embedded so as to maintain the clamp in position, so that the weft thread or the releasing blade which is arranged on either side of the selvedge can enter and pass between the prongs 5 of the clamp either from one end or from the other, the elasticity of the contact between the two prongs 5 being increased, by means of auxiliary springs 6.

Below this clamp, the ends of which may be extended into the slots 2 and 3, a cutting blade 7 (Fig. 3) is arranged in the bottom of each of the said slots.

According to Figures 5 to 9, which have reference to the members which present, release and cut the weft, these members comprise an eyelet 8 and a flexible blade 9, (Figs. 6 and 9), which are always placed together in groups and in such manner that one such group is arranged near 30 each selvedge of the woven material.

Each group of members 8 and 9 is mounted on a movable support 10 which slides, for example, in one of the caps 11 of the reed 12 and is controlled by a cam or lever not shown in the drawings and operated in conjunction with the movement of the reed or with the rotating members of the loom in such a way that the desired displacement of the support is obtained and accordingly the eyelet 8 or the blade 9 are located in suitable position, in accordance either with the entry of the inserting member 1 into the shed or with its exit from it. In certain cases each of the members 8 and 9 may be mounted on an independent movable support.

At the moment when the weft inserting member 1 is thrown into the shed, Figs. 5 and 6, the weft inserting member 1 is situated at the end of the conduit 13 (Figs. 5, 7, and 8) which forms the shuttle box—(the throwing member with discs or the like, is not shown in the drawings), the support 10 is in the position shown in Fig. 6, said support moving the blade 9 into an inoperative position and the eyelet 8 into a position where it presents the thread which passes from the point of the fell of the cloth 14 to the bobbin 15; the thread passes into one of the slots 2 or 3 of the weft inserting member 1, and is held between the prongs 5 of the clamp where the thread remains fixed until it arrives at the other selvedge.

By the operation of the adjacent cutting blade 7, which is arranged in the slot 2 or the slot 3 of the weft inserting member 1, the weft is then cut while the end of the preceding shoot is bent back towards the inside of the shed for the purpose of forming a selvedge.

Fig. 7 shows the weft inserting member 1 while it is passing through the shed.

When the shoot has almost passed through, the weft inserting member 1 has reached the end of its travel (Figures 8 and 9) the support 10 (Fig. 9) having been displaced in such a way as to place the eyelet 8 outside the path of movement of the member 1, thus moving aside the weft thread between the point of the fell of the cloth 75 and the bobbin, the blade 9 thereby having been

brought into juxtaposition with one of the slots 2 or 3 of the weft inserting member 1; the blade 9 penetrates between the prongs 5 of the clamp and moves them aside thus releasing the end of the shoot which has been passed across 5 the shed, and which comes out through the opposite slot whilst the weft inserting member 1 enters its box.

In the position shown in Fig. 8, the weft passes above the weft inserter, as it is raised by the 10 eyelet 8 off the path of the inserter, as in Fig. 9, so as to permit said inserter to pass out of the shed into the conduit 13, the releasing blade 9 having been brought in line with the groove 4 of the inserter 1 (Fig. 9). 15

When the inserter works on the reverse direction, it comes out of the box 13, and catches the thread which is stretched between the point of the fell of the cloth 14 and the bobbin 15 through the eyelet 8 which has been lowered, as shown 20 in Figs. 5 and 6.

Any means for actuating the movable support 10 sliding in one of the caps of the reed 12, may be employed.

A device of a somewhat different construction 25 is illustrated in Figures 10 and 11 of the drawings. In accordance with this modification, the inserting member 1 is not provided with cutting blades 7. Instead of these blades, a cutting blade 16 is operatively arranged on a support, adjacent 30 each side of the selvedges (Figures 10 and 11) and cuts the weft as described in the above mentioned patent application Ser. No. 673,672.

It is understood that without departing from the spirit of the present invention, changes, modifications or improvements can be made and in 35 the same way equivalent means can be applied.

Thus, for example, the single clamp 5 of the weft inserting member 1, could be replaced by two clamps, one being arranged in the extension 40 of the other.

In the same way, for example, and as shown in Figures 12 to 16, the weft inserting member 1' could have the same shape and cross section as the member shown in Figures 1 to 4, with the difference that its two end slots 2' and 3' are oblique in relation to the height of the member and issue on the side which slides along the reed 12 (Figs. 6, 9, and 11), to the right and to the left of the centre line, there being the further 50 difference that each of these slots communicates with a groove 4' or 4'' respectively, arranged also to the right and to the left respectively of the centre line, the said slots 2' and 3' issuing, on the side towards the fell of the cloth, on or very 55 near to the central plane of the weft inserting member 1'.

Two clamps 5' and 5'' formed in the same way as the clamp 5 are arranged in these slots, so as to allow the releasing blade 9 to pass through.

With this modified type of inserting member 1', the eyelets 8 and the blades 9 for presenting and releasing the weft are fixed and arranged on fixed supports on each side of the selvedges, in such a way that, as regards the group relating to the 65 right selvedge, the eyelet is in line with the slot 2' and the groove 4', whilst the blade is in line with the slot 3' and the groove 4'', so that it is able to separate the prongs of the clamp 5'' when the weft inserting member which is thrown from 70 the left selvedge, leaves the right selvedge to re-enter its box. The weft thread, which is not able to penetrate the groove 4', slides underneath the weft inserter while the latter is re-entering its box. Then the weft inserter is drawn from right 75

to left; the thread which is lightly stretched is able to penetrate the slot 2' in the course of this movement, reaching the clamp 5', and is cut by the cutting blade.

5 As regards the group relating to the left selvedge, the eyelet is arranged in line with the slot 3' and the groove 4'', whilst the blade is in line with the slot 2' and the groove 4' so that it is able to separate the prongs of the clamp 5' 10 when the weft inserting member 1' which is thrown from the right selvedge, leaves the left selvedge to re-enter its box. The weft thread, which is not able to penetrate the groove 4'' slides above the weft inserter while the latter is re-entering its box. Then the weft inserter is thrown from left to right; the thread which is lightly stretched, is able to penetrate the slot 3' in the course of this movement, reaching the clamp 5'', and is cut by the cutting blade.

15 20 I claim:

1. In shuttleless looms for continuously feeding the weft shots, in combination with a shed, and a pair of bobbins placed on both sides of the loom, the weft threads fed from said bobbins being stretched in front of both ends of the shed from the selvedges of the last pick at the fell of the cloth to said bobbins: a device for inserting single wefts and weaving from both sides of the loom, said device comprising a weft inserter for alternately gripping said threads, cutting means carried by said weft inserter, that part of each weft thread which alternately stands between the weft inserter and the selvedge being bent into the shed by the weft inserter while said weft inserter enters the shed, the part of the weft situated between its bobbin and the weft inserter being passed by said weft inserter through said shed as a single weft, and means for releasing the last-mentioned part of the weft from said weft inserter after it has passed through the shed.

2. In a weft inserting device, a weft inserter having a metal body of a substantially angular cross-section, said body being split vertically at its two ends, whereby a double pronged rider having two slots is formed, and means forming a groove in said body, said groove extending longitudinally between and connecting the said slots, whereby the weft thread may pass through said opposing slots.

3. In a weft inserting device, a weft inserter having a metal body of a substantially angular cross-section, said body being split vertically in its middle plane at its two ends, whereby a double pronged rider having two slots is formed, the middle portion of said body having a longitudinal central groove, said groove being in the longitudinal central plane passing through said slots, and a clamp carried by said weft inserter and situated in said groove; said clamp comprising two parallel resilient prongs which are in contact with each other, the ends of said prongs being bent toward the walls of said groove to maintain said clamp in position in the middle of said groove.

4. In a weft inserting and cutting device, a weft inserter having a metal body of a substantially angular cross-section said body being split vertically in its middle plane at its two ends, whereby a double pronged rider having two slots is formed, the middle portion of said body having a longitudinal central groove, said groove being in the longitudinal central plane passing through said slots, a clamp carried by said weft inserter and situated in said groove, said clamp comprising two parallel resilient prongs which are in contact

with each other, the ends of said prongs being bent toward the walls of said groove to maintain said clamp in position in the middle of said groove, and a pair of cutting blades carried by said weft inserter, each blade being situated at the bottom 5 of each slot between the clamp and the face of the inserter facing the fell of the cloth.

5. In shuttleless looms for continuously feeding the weft shots, in combination with a shed, and a pair of bobbins placed on both sides of the 10 loom, the weft threads fed from said bobbins being stretched in front of both ends of the shed from the selvedges of the last pick at the fell of the cloth to said bobbins; a device for inserting single wefts and weaving from both sides of the 15 loom, said device comprising a weft inserter for alternately gripping said threads, said weft inserter having a metal body of a substantially angular cross-section, said body being split vertically at its two ends, whereby a double pronged 20 rider having two slots is formed, the middle portion of said body having a longitudinal central groove, said groove being in the longitudinal central plane passing through said slots, a clamp carried by said weft inserter and situated in said 25 groove, said clamp comprising two parallel resilient prongs which are in contact with each other, the ends of said prongs being bent toward the walls of said groove to maintain said clamp in position in the middle of said groove, cutting 30 means carried by said weft inserter, that part of each weft thread which alternately stands between the weft inserter and the selvedge being bent into the shed by the weft inserter while said weft inserter enters the shed, the part of the weft 35 situated between its bobbin and the weft inserter being passed by said weft inserter through said shed as a single weft, and a pair of movable weft releasing blades, each blade being adapted to pass through a separate slot and penetrate between 40 the resilient prongs of the clamp as the weft inserter comes out of the shed to release the last-mentioned part of the weft from said weft inserter after it has passed through the shed.

6. In shuttleless looms for continuously feeding 45 the weft shots, in combination with a shed, and a pair of bobbins placed on both sides of the loom, the weft threads fed from said bobbins being stretched in front of both ends of the shed from the selvedges of the last pick at the 50 fell of the cloth to said bobbins; a device for inserting single wefts and weaving from both sides of the loom, said device comprising a weft inserter for alternately gripping said threads, cutting means carried by said weft inserter, that 55 part of each weft thread which alternately stands between the weft inserter and the selvedge being bent into the shed by the weft inserter while said weft inserter enters the shed, the part of the weft situated between its bobbin and the 60 weft inserter being passed by said weft inserter through said shed as a single weft, a pair of movable thread guiding eyelets situated at both ends of the shed, said eyelets placing the threads stretched between the fell of the cloth and the 65 bobbins alternately in and out of the path of the weft inserter, and means for releasing the weft from said weft inserter after it has passed through the shed.

7. In shuttleless looms for continuously feed- 70 ing the weft shots, in combination with a shed, and a pair of bobbins placed on both sides of the loom, the weft threads fed from said bobbins being stretched in front of both ends of the shed from the selvedges of the last pick at the fell of 75

the cloth to said bobbins; a device for inserting single wefts and weaving from both sides of the loom, said device comprising a weft inserter for alternately gripping said threads, cutting means carried by said weft inserter, the part of the weft situated between its bobbin and the weft inserter being passed by said weft inserter through said shed as a single weft, a pair of weft releasing blades, each blade being adapted to pass through a separate slot and penetrate between the resilient prongs of the clamp as the weft inserter comes out of the shed to release the last-mentioned part of the weft from said weft inserter after it has passed through the shed, a pair of movable thread guiding eyelets situated at both ends of the shed, said eyelets placing the threads stretched between the fell of the cloth and the bobbins alternately in and out of the path of the weft inserter, and a pair of movable supports, each support carrying a releasing blade and a guiding eyelet.

8. In shuttleless looms for continuously feeding the weft shots, in combination with a shed, and a pair of bobbins placed on both sides of the loom, the weft threads fed from said bobbins being stretched in front of both ends of the shed from the selvedges of the last pick at the fell of the cloth to said bobbins; a device for inserting single wefts and weaving from both sides of the loom, said device comprising a weft inserter having gripping means at each end for alternately gripping said respective threads, cutting blades mounted independently of the inserter on both sides of the selvedges at the entrances to the shed between the point of the fell of the cloth and the path of the inserter for cutting a weft extending between the selvedge and a bobbin close to the selvedge, the leading end of the part of the weft extending to the bobbin being gripped by said inserter and passed thereby through said shed as a single weft, and means for releasing the last-mentioned part of the weft from said weft inserter after it has passed through the shed.

45 9. In shuttleless looms for continuously feeding the weft shots, in combination with a shed, a reed and a pair of bobbins placed on both sides of the loom, the weft threads fed from said bob-

bins being stretched in front of both ends of the shed from the selvedges of the last pick at the fell of the cloth to said bobbins; a device for inserting single wefts and weaving from both sides of the loom, said device comprising a weft inserter for alternately gripping said threads, said weft inserter comprising two slots situated to the right and left of the central line of the weft inserter and extending obliquely with respect to the height of the weft inserter toward that surface of the weft inserter which slides along the reed, a pair of grooves being formed on a surface of the weft inserter, each groove forming a continuation of a separate slot, a pair of clamps for gripping the weft and carried by the weft inserter, each clamp being situated in a separate slot, a pair of cutting blades carried by said weft inserter, each cutting blade being situated at the bottom of each of the slots, a pair of fixed eyelets situated at both ends of the shed, and a pair of fixed weft releasing blades situated at both ends of the shed.

10. In shuttleless looms for continuously feeding the weft shots, in combination with a shed, a reed and a pair of bobbins placed on both sides of the loom, the weft threads fed from said bobbins being stretched in front of both ends of the shed from the selvedges of the last pick at the fell of the cloth to said bobbins; a device for inserting single wefts and weaving from both sides of the loom, said device comprising a weft inserter for alternately gripping said threads, said weft inserter comprising two slots situated to the right and left of the central line of the weft inserter and extending obliquely with respect to the height of the weft inserter toward that surface of the weft inserted which slides along the reed, a pair of grooves being formed on a surface of the weft inserter, each groove forming a continuation of a separate slot, a pair of clamps for gripping the weft and carried by the weft inserter, each clamp being situated in a separate slot, a pair of cutting blades operatively arranged at both edges of the cloth adjacent the selvedges, a pair of fixed eyelets situated at both ends of the shed, and a pair of fixed weft releasing blades situated at both ends of the shed.

RAYMOND DEWAS.
